UNITED STATES PATENT OFFICE.

CHARLES E. BENTLEY, OF NEW YORK, N. Y.

STAMPED FABRIC.

No. 869,225.

Specification of Letters Patent.

Patented Oct. 29, 1907.

Application filed February 10, 1906. Serial No. 300,525.

To all whom it may concern:

Be it known that I, CHARLES E. BENTLEY, a citizen of the United States of America, residing at the city of New York, county and State of New York, have invented certain new and useful Improvements in Stamped Fabrics, of which the following is a specification.

This invention relates to that class of fabrics bearing stamped or printed designs to be worked in embroidery or other ornamentation. This stamping is commonly done by laying upon the face of a fabric a stencil usually made of paper and then scraping or wiping a suitable semi-fluid compound through the stencil perforations to imprint the design upon the fabric.

15 In stamping designs upon linen or other fabrics it is desirable to have the lines so printed that all lines left uncovered by the finished embroidery or ornamentation may be easily washed out or eliminated by using water obtainable anywhere at any time.

20 By employing a metal block, such as is used for the printing of wall-papers, a design may be printed upon a fabric in a water-color and the desired results as regards easy washing out of the unworked lines of the design thus may be obtained, but such block-printing method is very expensive and therefore is quite impracticable for stamping or printing embroidery designs upon linen or other fabrics. Another process is to produce the design upon a fabric through a paper stencil by using a pounce of felt charged with coloring

25 matter, such as prussian blue mixed with powdered resin, the pounce being rubbed over the stencil to force the powder through its perforations to imprint the design which later is fastened to the fabric by application of heat. This process saves the expense of the 30 blocks used in block-printing but is much slower and more expensive than the process now in common use. This common process consists in mixing a paste of oil, or common oil paint, with suitable coloring matter to a proper consistency, and then forcing this oil paste 35 compound through the perforations of a paper stencil by a scraper or squeegee to imprint the design upon an underlying fabric. This last named process is rapid and inexpensive and the imprinted designs are clear and uniform in outline, but they are exceedingly difficult to wash out of the fabric. A water-color paste, such as is used in block-printing, cannot be employed instead of oil paint with a paper stencil because the water 40 in the color quickly wrinkles and ruins such a stencil.

45 It is the special object of this invention to provide a fabric stamped or imprinted in such manner, and by using such a peculiarly compounded printing matter scraped over a stencil, as shall permit unworked or unornamented portions of the stamped or imprinted design to be easily washed by water from the finished 50 55 embroidered fabric without injuring it or its ornamentation, while at the same time assuring durability of

paper stencils preferably used in applying the compound to the fabric to imprint the design thereon.

The invention will first be described and then will be particularly defined in claims hereinafter set forth. 60

Reference is made to the accompanying drawings forming part of this specification, and which is a plan or face view of a stamped fabric portions of the design upon which are embroidered, and having other and presumably washed out portions of the design indicated by dotted lines.

In the drawing, the numeral 1, indicates a piece of linen, silk, prepared leather or other fabric upon the face of which a design 2 has been imprinted by scraping a semi-fluid colored substance through perforations 70 of a paper stencil overlying the fabric. Portions 3 of this imprinted design have been embroidered or worked ornamenteally in any desired manner, and other minor portions 4 of the design, intentionally left unworked or unornamented, are shown by dotted lines which indicate that all such parts 4 of the originally imprinted design have been washed out after all the desired embroidery or ornamentation is finished.

The improved semi-fluid substance used to imprint designs 2 upon fabrics 1, in accordance with this invention, comprises an oleaginous saponified compound usually having incorporated coloring matter assuring distinctively visible imprints upon differently colored fabrics.

A preferred method of compounding this improved 85 fabric printing matter consists in melting a suitable quantity of oleaginous substance, preferably pure lard, and adding to the melted or softened lard a sufficient quantity of lye of soda or potash to saponify the mixture, and then preferably adding suitable coloring matter, 90 such as cobalt blue or lampblack, and stirring and thoroughly mixing the whole semi-fluid mass which forms a soft and smooth emulsion which can be worked with a paper stencil in the same way as common oil paint is used and without injuring the stencil. When this oleaginous 95 saponified compound cools sufficiently to have proper fluid consistency, it is wiped over a paper stencil by a scraper or squeegee to imprint a design upon a fabric underlying the stencil.

Practice has fully demonstrated that designs stamped 100 or imprinted upon fabrics by scraping or wiping this improved oleaginous saponified compound over a paper stencil laid upon the fabric, have clear or sharp and well-defined lines which are sufficiently fast-colored to guide the embroiderer or ornamenteer working 105 the design in or on the fabric. All unworked or unornamented portions of the design also may easily and quickly be washed from the finished fabric by the use of water without injuring it or its embroidery or ornamentation. Furthermore, this improved compound 110 does not clog or fill the perforations of paper stencils, and the compound does not shrink or ruin such

stencils as would a water-color, and the stencils therefore have the same durability as when the common oil paint compounds are used to imprint the design.

A further advantage of imprinting the design by application of this improved compound, is that designs so imprinted upon one fabric may be easily transferred to another or different fabric, as for instance, a design imprinted upon paper may be transferred from it at any future time by laying the paper face downward upon another fabric, and then slightly moistening the paper and pressing it with a hot iron, whereby the design will be transferred to the underlying fabric.

After using the common oil paint or paste compounds to print designs upon fabrics, all unworked portions of the design cannot be easily washed out or eliminated by water, and therefore the whole value of laboriously embroidered or ornamented fabrics is imperiled by the tedious washing process necessary to remove unworked portions of a design thus stamped in oil-color.

It is obvious that this invention fully meets or supplies a long-felt want or urgent need by providing means

for and method of using oleaginous matter with a paper stencil to clearly imprint designs upon fabrics without injuring the stencil, while at the same time permitting unworked or unornamented lines of the design to be 25 easily washed out to avoid injury to the finished fabric and by the use of water easily obtainable at any place where the stamped fabric pattern or design may have been worked by the embroiderer.

I claim as my invention:—

1. A fabric having an imprinted design produced by application of an oleaginous saponified compound, substantially as described, whereby unworked portions of the design may be readily washed from the finished embroidered fabric by water, as set forth. 30

2. A fabric having an imprinted design produced by application of a semi-fluid oleaginous saponified distinctively colored compound, substantially as described, whereby unworked portions of the design may be readily washed from the finished embroidered fabric by water, as set forth. 35
